(57) **CLAIM**

I claim the ornamental design for an optical scanner, as shown and described.

DESCRIPTION

FIG. 1 is a perspective front view of an optical scanner according to the present invention.

FIG. 2 is a top view of the optical scanner of FIG. 1.

FIG. 3 is a bottom view of the optical scanner of FIG. 1.

FIG. 4 is a right side elevation view of the optical scanner of FIG. 1.

FIG. 5 is a left side elevation view of the optical scanner of FIG. 1.

FIG. 6 is a front elevation view of the optical scanner of FIG. 1.

FIG. 7 is a rear elevation view of the optical scanner of FIG. 1.

FIG. 8 is a perspective front view of another embodiment of an optical scanner according to the present invention.

FIG. 9 is a top view of the optical scanner of FIG. 8.

FIG. 10 is a bottom view of the optical scanner of FIG. 8.

FIG. 11 is a right side elevation view of the optical scanner of FIG. 8.

FIG. 12 is a left side elevation view of the optical scanner of FIG. 8.

FIG. 13 is a front elevation view of the optical scanner of FIG. 8; and,

FIG. 14 is a rear elevation view of the optical scanner of FIG. 8.

Broken lines and unshaded portions contained within broken lines depict either parts of the optical scanner that form no part of the present claimed design or exemplary elements
